UNITED STATES PATENT OFFICE.

DONALD BARNS MORISON, OF HARTLEPOOL, ENGLAND.

WATER-HEATING AND THERMAL STORAGE APPARATUS.

Specification of Letters Patent. Patented Nov. 14, 1911.

1,008,851.

Application filed August 4, 1908. Serial No. 446,957.

To all whom it may concern:

Be it known that I, DONALD BARNS MORISON, a subject of the King of Great Britain and Ireland, residing at Hartlepool Engine and Works, Hartlepool, in the county of Durham, England, have invented certain new and useful Improvements in Water-Heating and Thermal Storage Apparatus, of which the following is a specification.

It is common practice in steam generating plants, especially at electric power stations, at periods of relatively light load, to pass steam, not then required for power purposes, into a reservoir containing feed water, the steam being admitted either above or below the water level and its latent heat utilized to raise the temperature of the water which is thereafter supplied to the boiler during a period of relatively heavy load, thereby enabling an evaporation rate to be obtained in the boiler considerably higher than the normal and a correspondingly greater supply of steam to be generated at a time when the power demands from the engine are at a maximum. Moreover, on a reduction of pressure, steam is re-generated in the reservoir and may be directly supplied to an engine. It is also common practice to employ exhaust steam for feed water heating purposes, the steam being supplied to the feed water heater either continuously or intermittently.

It often occurs that non-condensing steam engines, from the nature of their work, require to be run intermittently or irregularly, or that they exhaust at long intervals as in a slow running pumping engine, and that it is desired to utilize the exhaust steam from such an engine for power production, as for example, to drive a low pressure engine, or for use in injectors, or for other purposes. When however the supply of steam to the low pressure engine or other apparatus is at times irregular or intermittent, such irregularity is well known to be generally disadvantageous; and means have heretofore been adopted for improving the regularity of supply by means of thermal storage apparatus, (commonly known as regenerative accumulators), interposed between the non-condensing engine and the low pressure engine, or between the non-condensing engine and other exhaust steam-consuming apparatus, the steam being alternately condensed

and re-evaporated in the storage reservoir according to the relation between supply and demand.

The object of the present invention is to provide increased uniformity of steam supply available for such a low pressure engine or apparatus, by means of a novel combination of water heater and thermal storage apparatus adapted to usefully employ, as may be practicable, the maximum of the heat in the cycle comprising the boiler and condenser.

With this object in view, my invention consists in a novel arrangement of apparatus and combination of parts—more particularly set forth in the annexed claims—whereby when the supply of exhaust steam from the non-condensing engine exceeds that required by the low pressure engine or other steam consuming apparatus, some or all of the steam is automatically caused to overcome a head of, or otherwise mix with, water in a chamber containing feed or other water, and to pass into or through this water for the purpose of heating it, which action however ceases automatically whenever the exhaust steam supply is not in excess of that required by the low pressure engine, so that under these conditions of working there is no loss of steam pressure.

In the accompanying drawings, Figure 1 is a diagrammatic view illustrating the cycle of operations according to my invention and Fig. 2—also diagrammatic—illustrates a feed water supply arrangement.

Referring to Fig. 1, *a* is a steam generator which supplies steam by way of the pipe *b* to the high pressure engine *c*, which exhausts by way of the pipe *d*, *d*₁ directly to the low pressure engine *e*, herein shown as a turbine; or, when the supply of steam from the high pressure engine is greater than that required by the turbine, steam is led by way of the pipe *f* to the feed water heating and thermal storage apparatus *g*, where it is caused to overcome a head of, or otherwise mix with, water contained therein. Steam admitted to, and not condensed in, the apparatus *g*, and steam resulting from ebullition of water in the receiver, flows by the pipe *h* to the low pressure engine. The low pressure engine exhausts by way of the pipe *m* to the condenser *n*, which works in conjunction with the air pump *o*, which dis-

charges the water of condensation into the apparatus *g* by way of the pipe *p*. The heated feed water can leave the apparatus by way of the pipe *q*, and flow into the tank 5 *r*, whence it is supplied to the boiler by the feed pump *s* by way of the pipe *t*; thus completing the cycle. It will be seen that during this cycle the water enters or can enter the apparatus *g* twice, once in the form of steam, 10 and the other time in the form of water. This double passage through the apparatus is an important feature of the cycle of operations employed in carrying my invention into effect.

15 Instead of passing the whole of the water required for the boilers into the receiver, I may by-pass some of this by way of the pipe 13, Fig. 1, the amount so by-passed being capable of being regulated by means of 20 the three way cock 14. Non-return valves 15 and 16 are preferably provided on the pipes *d* and 13. This water passed into the receiver may advantageously consist of feed water drawn from the condenser of the low- 25 pressure engine or from other apparatus in which the steam from the non-condensing engine or the thermal storage reservoir is ultimately condensed, which water may be supplemented by auxiliary feed water. In 30 order that the available heat in the exhaust steam may be absorbed by the water in the apparatus without an excessive variation in the exit temperature of this water, it is usually desirable to construct the apparatus 35 so as to contain a quantity of water which is considerable with respect to the average rate of supply of the steam.

k is an automatic valve for controlling the supply of steam to the apparatus *g* and to 40 the low pressure engine in accordance with the relation between supply and demand. This valve is suitably disposed on the pipe *d*, between the branches *f* and *h* or at the junction of the pipes *d*, *d*, and *f* and is controlled by the steam pressure in the pipe *d*, or by the governor of the low pressure engine, so that, when the exhaust steam supply from the non-condensing engine is equal to, or less than, the demands of the low pressure 45 engine, the valve acts to throttle or cut off the direct flow of steam from *d* to *d*, and thus cause steam to pass into the receiver *g*.

If the pressure in the receiver is liable to fall considerably below atmosphere, it may 50 be inconvenient or impossible to maintain a constant water level in the receiver by means of the arrangement illustrated in Fig. 1; and I may then, or in any other case when desired, otherwise control the water level as 55 by means of a float-actuated valve on the water admission pipe. This arrangement is shown in Fig. 2, where 20 is a pump which delivers the condensed steam from the low pressure engine into the tank 18; 19 is the 60 pipe for conveying the water from this tank

to the thermal apparatus *g*; 21 is a pipe with a hand-controlled valve 22 for allowing a controllable portion of the water to pass from the tank 18 to the pipe 23, whence it flows direct to the boiler feed tank *r*, and 24 is an overflow pipe from the tank 18 to the pipe 23.

Having now described my invention, what I claim as new and desire to secure by Letters Patent is:—

1. In combination, a high pressure steam engine, a water-heating and thermal-storage apparatus, a low pressure steam engine, a pipe for delivering steam from the exhaust of the high pressure engine to the thermal-storage apparatus, and a pipe for delivering steam from the thermal-storage apparatus to the low pressure engine, and another pipe connected so that steam may be passed from the exhaust of the high pressure engine to the low pressure engine without passing into the thermal-storage apparatus, and means for automatically varying the ratio of the quantity of steam passing into the thermal-storage apparatus to the quantity of steam passing directly from the high pressure engine to the low pressure engine with variations in the ratio of the quantity of steam supplied by the exhaust of the high pressure engine to the quantity of steam taken by the low pressure engine.

2. In combination, a high pressure steam engine, a water heating and thermal-storage apparatus, a low pressure steam engine, a pipe for delivering steam from the exhaust of the high pressure engine to the thermal storage apparatus, a pipe for delivering steam from the thermal-storage apparatus to the low pressure engine, a branch pipe connecting said pipes together so that steam may be passed from the exhaust of the high pressure engine to the low pressure engine without passing into the thermal-storage apparatus, and means in said branch pipe for automatically varying the ratio of the quantity of steam passing into the thermal-storage apparatus to the quantity of steam passing directly from the high pressure engine to the low pressure engine with variations in the ratio of the quantity of steam supplied by the exhaust of the high pressure engine to the quantity of steam taken by the low pressure engine.

3. In combination, a high pressure steam engine, a water heating and thermal storage apparatus, a low pressure steam engine, a pipe for delivering steam from the exhaust of the high pressure engine to the thermal-storage apparatus, a pipe for delivering steam from the thermal storage apparatus to the low pressure engine, a branch pipe connecting said pipes together so that steam may be passed from the exhaust of the high pressure engine to the low pressure engine without passing into the thermal storage ap-

paratus, and a steam controlled valve for automatically varying the ratio of the quantity of steam passing into the thermal-storage apparatus to the quantity of steam passing directly from the high pressure engine to the low pressure engine with variations in the ratio of the quantity of steam supplied by the exhaust of the high pressure engine.

to the quantity of steam taken by the low pressure engine. 10

In testimony whereof, I affix my signature in presence of two witnesses.
